UNITED STATES PATENT OFFICE.

WILLIAM H. DILLON, OF DETROIT, MICHIGAN.

BEAM CLAMP AND SUPPORT FOR REINFORCED CONCRETE FORMS.

No. 825,284.

Specification of Letters Patent.

Patented July 8, 1906.

Application filed February 10, 1905. Serial No. 245,001.

To all whom it may concern:

Be it known that I, WILLIAM H. DILLON, a citizen of the United States, residing at 56 Trowbridge avenue, in the city of Detroit, county of Wayne, and State of Michigan, have invented a new and useful Beam Clamp and Support for Concrete Forms, of which the following is a specification.

The invention relates generally to a form or mold support for beams or floors in reinforced concrete construction; and it consists in the novel and simple construction of support, in the peculiar formation of the mold-supporting devices, and in other details of construction, as will be more fully herein-after set forth and illustrated.

In the drawings, Figure 1 is an elevation of an embodiment of my invention, showing the beam-box, floor-joist, and upright supporting post or member in place. Fig. 2 is a side elevation illustrating the joist-seat on the beam-support. Fig. 3 is a plan of the post-cap; and Fig. 4 is a perspective view of the apparatus as in use, the post being shown in section.

In the drawings thus briefly described, *a* represents an upright, which supports the other parts of the apparatus. Fitted upon the upright or post-top is a detachable cap *C*, the construction of which will be more fully herein-after set forth, and extending transversely of the cap and having preferably detachable connection therewith is the supporting member *b*, upon which are supported the mold-supporting devices or members *A* and *B*.

The cap referred to is formed from a single sheet-metal blank which is cut and shaped in such manner as to form a top *a'*, sides *b'*, and ends composed of complementary angle-shaped sections *c' d'*, spaced apart, as indicated in Figs. 3 and 4, and extending at their upper ends beyond the cap-top. Bolts *e'*, extending through the lower portions of the angle-shaped sections described, hold the cap in place on the upright, while similar bolts *d* are adapted to connect the cap to the transverse supporting member *b*, previously referred to. This supporting member is preferably in the form of a T-bar the web portion of which fits between the sections of the cap and is held in place by the bolts *d*, engaging the cap and extending through the bar-web.

The mold-supporting members *A* and *B* are adjustable longitudinally upon the beam *b* to fit and support any size of mold, as *D*, in

which the concrete is placed. Preferably each support is composed of a main supporting section or side member, as *a*², having a T-shaped opening *a*³, formed in its lower portion to permit of the engagement with the T-bar, an inclined brace-section *b*², spaced at its lower end from the main side section, and an intermediate member, as *b*³, supported by one or both of the sections, forming a seat for a joist, as *h*, of the floor-form.

The intermediate portion or seat-section *b*³ is formed, preferably, by an integral portion of the member *b*², bent into parallelism with the main beam *b*' and riveted or otherwise secured to the section *a*².

The brace-sections referred to are provided with inturned portions *a*⁴, engaging beneath the flange of the bar *b*, which serves to hold the parts in the proper position upon the main beam. For the purpose, however, of positively locking the mold-supporting devices or members after a proper adjustment has been effected pins, as *a*⁵, may be employed, extending through the web of the bar *b* and forming an abutment or stop for the mold-supporting devices.

In the construction of the building apparatus set forth it will be obvious that the parts may be readily detached, the post being removed from the cap by forcing its lower end to one side to permit of its withdrawal, while the beam is detached from the cap and from the mold-supporting devices in the manner previously set forth.

What I claim as my invention is—

1. In building apparatus of the character described, the combination with an upright, of a transverse member supported thereon, and vertical mold-supporting devices upon the transverse member provided with joist-seats.

2. In building apparatus of the character described, the combination with an upright, of a transverse bar thereon, vertical mold-supporting devices adjustably mounted upon the bar, and oppositely-extending supporting members carried by said devices forming joist-seats.

3. In building apparatus of the character described, the combination with an upright, of a detachable cap therefor, a transverse bar mounted upon and having detachable connections with the cap, and adjustable mold-supporting devices or members upon the bar.

4. In building apparatus of the character

described, the combination with an upright provided at its upper end with a vertical horizontally-extending opening, of a transverse member detachably arranged within 5 said opening, and complementary mold-supporting devices mounted upon said member for longitudinal adjustment.

5. In building apparatus of the character described, the combination with a vertical 10 post, of a longitudinally-slotted cap detachably mounted upon the upper end, a horizontal T-bar arranged upon the cap with its web engaging the slot, securing devices engaging the cap and the bar-web, and adjustable mold-supporting members upon the T-bar.

6. In building apparatus of the character described, the combination with an upright, 15 of a transverse member detachably mounted thereon, and mold-supporting devices adjustably arranged upon said member.

7. In building apparatus of the character described, the combination with an upright, 20 of a detachable cap thereon, a transverse member supported upon the cap, and mold-supporting devices upon said member.

8. In building apparatus of the character described, the combination of a transverse member, and complementary mold-supporting 25 devices thereon each provided with a lateral outwardly-opening joist-seat.

9. In building apparatus of the character described, a mold-supporting device comprising a main section, a brace-section therefor, and an intermediate member carried by 30 the sections and forming a joist-seat.

10. In building apparatus of the character described, a mold-supporting device comprising a main upright section, an inclined

brace-section therefor, and an intermediate 40 seat member connecting the lower portions of the main and brace sections and adapted to receive longitudinally thereof a joist.

11. In building apparatus of the character described, the combination with an upright, 45 of a cap upon its upper end, a transverse bar supporting and having detachable connections with the cap, and mold-supporting devices upon said bar.

12. In building apparatus of the character 50 described, the combination with an upright and a cap therefor comprising a top, sides, and ends formed of spaced angle-sections extending beyond the top, the sections being arranged with the openings or spaces in aline- 55

ment.

13. In building apparatus of the character described, a post-cap formed from a single sheet of metal comprising a top, sides, and ends having complementary spaced sections 60 extending beyond the cap-top.

14. In building apparatus of the character described, the combination with an upright, 65 of a detachable sheet-metal cap for its upper end comprising a top, sides and ends composed of spaced angle-shaped sections extending upwardly beyond the top, a transverse bar arranged between the cap extensions, and complementary mold-supporting members mounted upon the bar for longitudinal adjustment.

In testimony whereof I have signed my name to this specification in the presence of two subscribing witnesses.

WILLIAM H. DILLON.
